HEINRICH DREWELL, OF CHARLOTTENBURG, GERMANY.

ELECTRIC SWITCH.

No. 876,701.

Specification of Letters Patent.

Patented Jan. 14, 1908.

Application filed March 9, 1907. Serial No. 361,589.

To all whom it may concern:

Be it known that I, HEINRICH DREWELL, subject of the German Emperor, residing at Charlottenburg, Germany, have invented 5 new and useful Improvements in Electric Switches, of which the following is a specification.

The present invention relates to means for closing an optional branch of a multiple branched circuit by means of a limited number of switches.

An important object of the connection in accordance with the present invention is to control the branches of a divided circuit with 15 a number of switches or interrupters which is smaller than the number of the branches.

In certain connections which are already known there are switches which can operate simultaneously and which accordingly may 20 be mechanically connected one with another. One part of these switches has moreover the characteristic feature that the one switch-pole consists of a plurality of contacts which are insulated one from another when the 25 switch is open, the other pole on the contrary consisting only of one common piece. If the insulated contacts are connected when the switch is open, shunts are formed which are capable of disturbing the intended manner 30 in which the switches should operate. An important object of the present invention is to remove this disturbing effect of the shunts. It is attained by inserting devices in all the branches of the circuit which are 35 capable of forming shunts, said devices permitting the passage of an electric current in only one direction. Such a device is, for example, an electrolytic cell with an aluminum electrode, so-called "valve-cell", or an 40 arrangement in which a loose carbon contact is influenced by a polarized magnet or the like.

In order that the invention may be clearly understood reference is made to the accompanying drawing in which two connections in accordance with the present invention are shown diagrammatically by way of example in Figures 1 and 2.

Referring to Fig. 1, *a* and *b* are branching points of the circuit in which the battery *f* is situated, to each of which points a series of three switches, *c* and *d* respectively, are connected. These switches are on the other hand connected with the individual 55 branches 1 to 9 of the circuit, namely, each

with one group of three branches. The branches 1 to 9 contain all the devices *e*, valve-cells or other devices, which allow an electric current to pass in one direction only. Now in order that only one branch may 60 receive current when two switches are closed, one switch being at *a* and one at *b*, the connection must be such that each group of branches, which for example is connected by one of the switches *c* to the one pole of the 65 source of current *f*, has one of the branches 1 to 9 in common with each of the groups which are connected by the switches *d* to the other pole of the source of current *f*. It follows from this, of course, that the groups 70 of branches at the switches *c* and *d* must be differently composed. If two switches are closed, the one being at *c* and the other at *d*, that branch which is common to the connected groups makes a connection between the points 75 *a* and *b* and thus between the poles of the source of current; this branch therefore receives current. Shunts however exist in this connection. For example, when the center switches *c* and *d* are closed, a current 80 can on the one hand pass directly along the branch 5 from *a* to *b*. Further, the additional paths over the branches 4, 1, 2 and 6, 9, 8, for example, are possible for the current. These are shunt circuits, and in order 85 to be able to pass them the current must flow in the branches 1 and 9 in a direction opposite to the normal direction from *a* to *b*. Consequently such shunt circuits are nullified when valve-cells, or other devices *e*, 90 are inserted in the branches 1 to 9 which allow an electric current to pass in one direction (from *a* to *b*) only.

Fig. 2 shows another connection employing like means for nullifying shunt circuits. 95 The switches *g* and *h* in Fig. 2 take the place of the switches *c* and *d* in Fig. 1. The switches *h* are here dependent on the switches *g* in such a manner that when one of the switches *g* (with the exception of the first) 100 is closed, a switch *h* is simultaneously operated by the action of coils *i*, the circuits of these coils being closed by the switches *g*. The branches I to XV of the circuit of the battery *l* are connected in groups with the 105 switches *g* and *h*. The groups of the branches are in this case so formed and connected that each of the groups of branches which are connected to one of the switches *g* has one branch in common with all the 110

groups of branches which are connected with switches h of higher number than that of the concerned switch g . Every one of the branches I to XV may be closed by the simultaneous action of two switches g . For example branch VIII is closed by the action of the 2nd and 5th switches g . These switches, when closed, will electrically operate the 2nd and the 5th of the switches h and current may flow through the second switch g , the branch VIII and the 5th switch h .

If no valve-cells or similarly operating devices were employed, there would be several shunts if any pair of the switches g is closed. For instance, if the second and fifth of the switches g are closed, the electric current might flow through the second switch-contact g to the branches V, VI, VII and IX and from the branches backward through the branch II to the branch III and from here to the fifth of the switches h , which is closed by the corresponding coil i connected to the fifth switch g . The branches VI and VII form further unintended shunts. To form any one of the shunts however it is necessary that the electric current can flow through one of the branches I to IX opposite to its normal direction. These shunts may therefore be avoided by inserting in the branches I to XV devices k , through which the electric current can pass in one direction only.

It is evident that in both arrangements, shown in Figs. 1 and 2, the number of switches, conductors, shunts, and devices (e or k) may be increased or diminished in a suitable manner for any given purpose without departing from the spirit and scope of the present invention.

The above described connections in accordance with the present invention may be employed for transmitting combinations of telegraphic current in type-printing, as well as for the automatic operation of typewriting and type setting machines, in which machines keys are to be struck and types or matrices are to be released according to the combination of holes of a register band.

What I claim as my invention and desire to secure by Letters Patent is:

1. In means for closing an optional branch of a circuit which is divided into a plurality of branches, the combination of a series of switches, a source of current, conductors connecting said switches with one pole of said source of current, another series of switches, conductors connecting the latter with the other pole of said source of current and a plurality of branch conductors arranged in groups connected with said sets of switches in groups, each group of branches connected with the one series of switches having one branch in common with the groups of branches connected to the other series of

switches, with a plurality of devices adapted to permit the passage of an electric current in one direction only, one of said devices being inserted in each of said branches as set forth.

2. In means for closing an optional branch of a circuit which is divided into a plurality of branches, the combination of a series of switches, a source of current, conductors connecting said switches with one pole of said source of current, another series of switches, conductors connecting the latter with the other pole of said source of current and a plurality of branch conductors arranged in groups, said groups of branch conductors being each connected in order to switches of one of said series of switches and said branch conductors being connected in order in different groups to switches of the other series of switches, whereby shunts are provided for the current flowing in a branch directly from one of said series of switches to the other, with a plurality of devices adapted to permit the passage of an electric current in one direction only, one of said devices being inserted in each of said shunts as set forth.

3. In means for closing an optional branch of a circuit which is divided into a plurality of branches, the combination of a series of switches, a source of current, conductors connecting said switches with one pole of said source of current, a series of automatic switches each having an energizing coil, conductors connecting said automatic switches and one end of said coil with the other pole of said source of current, a plurality of conductors connecting the other end of said coils in order with all but one of said former series of switches, and a plurality of branch conductors arranged in groups connected with said set of switches in groups, each group of branches connected with the one series of switches having one branch in common with all the groups of branches which are connected to the switches of higher number of the other series than that of the concerned switch in the former series, with a plurality of devices adapted to permit the passage of an electric current in one direction only, one of said devices being inserted in each of said branches as set forth.

4. Means for closing an optional branch of a circuit which is divided into a plurality of branches, comprising in combination a series of switches, a source of current, conductors connecting said switches with one pole of said source of current, another series of switches, conductors connecting the latter with the other pole of said source of current, a plurality of branch conductors arranged in groups connected with said set of switches in different groups, each group of branches connected with the one series of switches having one branch in common with the groups of branches connected to the other series of

switches, whereby shunts are provided for the current flowing in a branch directly connecting two switches of said two series of switches, and a plurality of polarized cells; 5 one of the latter being inserted in each of said shunts as set forth.

In testimony whereof I have signed my

name to this specification in the presence of two subscribing witnesses.

HEINRICH DREWELL.
